UNITED STATES PATENT OFFICE.

ERNEST CANTELO WHITE, OF EVANSTON, ILLINOIS, ASSIGNOR, BY DIRECT AND MESNE ASSIGNMENTS, TO THE DUPLEX LIGHTING SYSTEM, INC., OF CHICAGO, ILLINOIS, A CORPORATION OF ILLINOIS.

LIGHTING-FIXTURE.

1,211,651.

Specification of Letters Patent.

Patented Jan. 9, 1917.

Application filed April 5, 1916. Serial No. 89,004.

To all whom it may concern:

Be it known that I, ERNEST CANTELO WHITE, a citizen of the United States, residing at Evanston, in the State of Illinois, 5 have invented certain new and useful Improvements in Lighting-Fixtures, of which the following is a specification, reference being had to the accompanying drawings, forming a part hereof.

10 Interior artificial lighting is generally accomplished by either direct lighting, in which the rays pass directly from the luminous point to the object, indirect lighting, in which the object is illuminated wholly by reflected rays, or semi-indirect lighting, in which the object is illuminated partially by reflected rays and partially by a luminous translucent reflector.

15 The present invention has to do with a fixture having a reflector of the same general character as that shown in U. S. Patent No. 1,168,939, issued to the present applicant on January 18, 1916, but seeks to improve the reflector for such a fixture in order to eliminate certain possible objections to such a reflector arising under certain conditions of use. The principal objections, briefly stated, are, first, that an opaque reflector having an opening in its bottom 20 through which the rays pass directly to the object, does not direct or focus these rays to any degree and, second, that the downwardly reflected rays through the opening are visible from all ordinary angles of view 25 and so impair the general softening effect peculiar to indirect and semi-indirect lighting. In accordance with the present invention, these main objections are overcome by providing a downwardly flaring secondary reflector for the rays for direct lighting, which reflector is of such character as to direct and focus these rays on the objects beneath the light and prevent the direct passage of rays of light to the eyes of an observer 30 at all ordinary angles of view. This secondary reflector for the direct rays is carried on the usual opaque or primary reflector for the indirect lighting and may, indeed, be either integral with such reflector or detachably secured thereto. Further, the secondary reflector may be either translucent or opaque. Where, as has been found effective 35 in practice, a translucent diffusing member is mounted in the opening in the bottom of

the opaque primary reflector for indirect lighting, this member may be either mounted removably on the opaque reflector, or where the secondary reflector is translucent, may be formed integral therewith, thereby constituting a unit adapted to be 40 detachably engaged with the primary reflector. All of these permissible substitutions and rearrangements will appear in greater detail in connection with the following description of two feasible embodiments of the 45 invention illustrated in the accompanying drawings, in which—

Figure 1 is a view of so much of a lighting fixture as is necessary for an understanding of the application thereto of the improved 50 reflector, the reflector being shown partly in section and partly in elevation. Fig. 2 is a view similar generally to Fig. 1 but showing a somewhat modified form of the secondary reflector for the rays for direct lighting, 55 this reflector being made integral with the translucent diffusing member.

As in the specification of the patent above identified, the term "object" is used in this specification to refer particularly to a 60 limited zone or area to be illuminated directly under the lighting fixture and the rays referred to are assumed, for convenience, to emanate from an electric light, although it is evident that any other source of 65 light may be used. The fixture, indicated generally at *a*, may carry a fitting *a'* from which extend supporting arms *a²* for the primary opaque reflector *b*. On the fixture *a* is also carried a lamp socket *a³* in which is 70 fitted the source of light *c*. In an indirect lighting fixture, as such, the reflector *b* would, in inverted position, present an unbroken reflecting surface, so as to throw all of the rays of light to the ceiling for reflection to the objects in the room to be illuminated. In other words, no rays of light 75 would be permitted to pass directly from the source of light *c* to any object.

In the improved fixture it is proposed to 80 retain all of the desirable features of indirect lighting by causing the inverted reflector *b* to divert a large percentage of the rays from the source of light and throw such rays to the ceiling from whence they 85 will be reflected to the objects in the room. However, it is often desirable even in rooms 90 having the softest lighting effects to have

available a limited field of direct lighting for the more intense illumination of objects directly beneath the fixture. Accordingly, the indirect lighting provided for by the 5 opaque reflector b is supplemented, in the applicant's fixture by providing an opening b' in the bottom of the reflector and directly beneath the source of light through which rays of light are reflected and permitted to 10 pass directly downward to the objects to be more intensely illuminated. Such rays of direct lighting will ordinarily be diffused so as to retain the soft effects of indirect lighting by means of a translucent member d disposed in said opening b' . The improved 15 reflector, as thus far described, is shown and claimed in the patent hereinbefore referred to.

The present application is concerned with 20 the improvement of a fixture of the general type described by the provision of a secondary reflector for the rays of light for direct lighting. In Fig. 1 such a reflector is formed as a downwardly flaring opaque 25 member b^2 integral with the reflector b . In this construction the diffusing member or plate d may rest on suitable flanges b^3 struck up from the opaque reflector b around the periphery of the opening b' . The reflector 30 b^2 for the rays for direct lighting, considered as an element independent of the indirect lighting reflector b , serves to redirect and focus those rays of light which are reflected downward from the lower portion of 35 the reflector b so as to create directly beneath the fixture a limited zone of direct lighting. To bring about the desired concentration and focusing, the contour of the reflector b may be changed as required to best 40 serve its purpose. In the drawings it is indicated as flaring downwardly in which form, when translucent, it also diffuses light on the exterior of the primary reflector b but it is evident that it may be cylindrical 45 and either of regular or irregular cross-sectional form. The translucent secondary reflector by throwing light on the exterior surface of the primary reflector thereby creates in this primary reflector an additional 50 source of diffused luminous lighting. Not only does the reflector b^2 serve the important function described in supplementing the indirect lighting by a useful element of direct downward lighting formed by rays 55 focused, but it also prevents any rays from passing directly to the eyes of an observer at any ordinary angle of view. Where the translucent plate d is employed, for instance, this plate may be considered, for convenience, the luminous point and, without the 60 secondary reflector b^2 , would appear as a source of direct lighting to the eyes of all observers at ordinary angles of view. Obviously, where the benefits of indirect lighting are sought to be obtained, it would 65

usually be objectionable to have the glare of such a luminous object in the room. This is especially true when, as in the case of nitrogen lamps, the brilliance is so intense as to preclude direct lighting. The improved 70 reflector b^2 conceals the translucent plate d at all ordinary angles of view so that the observer does not lose the ornamental effect of the entire fixture and his eyes are shielded from the glare of the direct rays. The 75 member d may be of any cross sectional form. If the plate d were omitted the secondary reflector would, nevertheless, serve to shade the luminous interior of the primary reflector which otherwise would be 80 partially visible at ordinary angles.

In Fig. 2, is shown a somewhat modified construction, in which all of the advantages peculiar to the improved fixture are retained. Fig. 2 simply illustrates one obvious departure from the construction shown in Fig. 1 without loss of the advantages of the invention, by making the reflector B^2 for the rays for direct lighting independent of the opaque reflector B for indirect lighting. In 85 this construction the downwardly extending reflector B^2 is detachably mounted on the opaque reflector B as by the engagement of thumb screws e carried by the opaque reflector B and engaging the downwardly extending reflector B^2 . In this embodiment it is indicated that the translucent plate D may be carried by the downwardly extending reflector B^2 so as to be detachable from the opaque reflector B with said reflector B^2 . A 90 further departure from the construction shown in Fig. 1 resides in the use of a translucent reflector B^2 for the rays for direct lighting. Where this reflector is translucent it is evident that the translucent plate 95 B may very conveniently be formed integral therewith. In the use of a translucent reflector B^2 all of the advantages of the invention are retained since this reflector will concentrate and focus the downwardly passing rays of light and also shield the eyes of the observer at all ordinary angles of view from the luminous plate D which receives direct rays from the light c at right angles to its plane. In this embodiment, 100 the benefits of indirect lighting are retained and the supplemental direct lighting beneath the fixture is secured in the most effective way.

Other changes in the details of construction and arrangement of parts may be made without departing from the spirit of the invention provided the advantages described are realized by means which fall within the appended claims.

I claim as my invention:

1. In a lighting fixture, the combination of a source of light, a primary reflector formed with opaque sides and a centrally disposed bottom opening, the said primary 130

- reflector housing the said source and reflecting a portion of the light therefrom upward, and a translucent secondary reflector carried by the primary reflector and 5 extending downwardly from the bottom thereof and intercepting a portion of the light rays which pass downward from the said source through the said opening.
2. In a lighting fixture, the combination 10 of a source of light, a primary reflector formed with a centrally disposed bottom opening, the said primary reflector housing the said source and reflecting a portion of the light therefrom upward and another 15 portion of the said light downward through the said opening, and a secondary reflector extending downwardly from the bottom of the primary reflector and intercepting a portion of the light rays reflected through the 20 said opening by the primary reflector.
3. In a lighting fixture, the combination 25 of a source of light, a primary reflector formed with opaque sides and a centrally disposed bottom opening, the said primary reflector housing the said source and reflecting a portion of the light therefrom upward and another portion of the said light downward through the said opening, and a translucent secondary reflector carried by 30 the primary reflector and extending downwardly therefrom and intercepting a portion of the light rays reflected through the said opening by the primary reflector.
4. In a lighting fixture, the combination 35 of a source of light, a primary reflector comprising opaque sides and a translucent bottom section, the said primary reflector housing the said source and reflecting upward a portion of the light therefrom, and a secondary reflector extending downwardly from the said primary reflector and intercepting a portion of the light rays transmitted from the said source through the translucent section of the said primary reflector. 40
- 45 5. In a lighting fixture, the combination of a source of light, a primary reflector com-
- prising opaque sides and a removable translucent bottom member and reflecting upward a portion of the light from the said source, and a secondary reflector formed integral with the said translucent bottom member and extending downwardly therefrom and intercepting a portion of the rays transmitted from the said source through the said translucent bottom member. 50
6. In a lighting fixture, the combination of a source of light, a primary reflector comprising upwardly flaring opaque sides and carrying a translucent member to form a bottom closure thereto and reflecting upward a portion of the light from the said source, and a translucent secondary reflector formed integral with the said translucent member and flaring downwardly from the bottom of the primary reflector. 60
7. In combination with a source of light, a lighting fixture having an inverted opaque reflector to throw rays of light upward, said reflector having an opening formed in its bottom to give a useful element of direct 70 downward lighting, a downwardly extending translucent reflector for the rays for direct lighting having its upper edge disposed within said opening, a flat translucent plate disposed in the opening and formed 75 integral with said translucent reflector, and devices carried by the opaque reflector for securing said translucent reflector and plate detachably to said opaque reflector.
8. In combination with a source of light, 80 a diffusing member positioned below the source of light and a reflector formed integral with the said diffusing member and extending downwardly therefrom so as to intercept all rays transmitted from the said 85 source through the said diffusing member and emitted therefrom in all directions above all ordinary angles of view.

This specification signed this thirtieth day of March, A. D. 1916.

ERNEST CANTELO WHITE.
